AUGUST LEIB, OF BERLIN, GERMANY, ASSIGNOR TO TELEFUNKEN GESELLSCHAFT FÜR DRAHTLOSE TELEGRAPHIE M. B. H., OF BERLIN, GERMANY, A CORPORATION OF GERMANY

WEATHERPROOF DIRECTION-FINDING ANTENNA

Application filed April 5, 1930, Serial No. 441,947, and in Germany May 8, 1929.

It is known in the prior art to enclose the turns of direction-finding antenna inside a weather-proof protective frame of round or polygonal, say, square shape, the constituent 5 sections of said frame being united with one another by separate joining pieces to result in a stiff structure. The mounting of antenna turns inside such protective frames is rendered difficult on account of the fact that 10 it is necessary to shift or thread the wires not only through all of the constituent frame parts, but also through the said connecting pieces.

Now, the present invention discloses ways 15 and means of facilitating the assembly of the weather-proof direction-finder antenna in that the pushing of the antenna or coil turns through the connecting pieces is obviated in that the latter consist of pairs of 20 shell pieces adapted to be attached together.

In mounting the loop the wire can be shifted quite readily through each of the separate sections or parts of the protective frame consecutively. Thereupon the whole is 25 brought into the desired final shape and is stiffened by applying the connecting or joining pieces the constituent shells of which are firmly united together.

A direction-finder coil or loop is illustrated 30 in the accompanying drawing. Fig. 1 shows a finished square protective frame according to the invention comprising straight limb pieces *a* and the angular knees *b*, and each of these latter consists of two shells *cc* as 35 shown in Fig. 2.

Of course, care should be taken so that the protective frame will form no closed conducting loop in electrical respect. For this purpose, one of said connecting pieces or 40 one of the pipe pieces or part thereof may be made of insulation material.

I claim:

1. A shield for a loop antenna including 45 a plurality of metallic tubular members, and means for joining said tubular members together comprising split members adapted to be clamped over the ends of said tubular members.

2. Means for substantially completely en- 50 closing a directional aerial system in an

electrostatic shield comprising, a plurality of metallic tubular members each adapted to be arranged with an end adjacent the end of another tubular member to produce a substantially closed composite member, and means 55 for retaining said members in position comprising split joints adapted to be clamped over the adjacent ends of the tubular members.
